APPARATUS FOR THE STERILIZATION AND
STERILE FILLING OF VESSELS AND THE
LIKE

Georg Gebhardt, Kreuznach, Germany

Application June 1, 1931, Serial No. 541,499
In Germany July 25, 1930

5 Claims. (Cl. 226—68)

In beer-cellar and wine-cellar management it is known for a long time to sterilize casks and bottles by injecting into them such an amount of sulphur dioxide corresponding to the size of the respective casks or bottles. If transport casks are sterilized in this manner it is nevertheless impossible to fill them with a sterilizing liquid because, on the one hand, germs and the like can find access into the cask through the bung opening, and on the other hand, the filling device placed into said opening is freely exposed to the open air after every filling so that it can be infected and convey the germs or the like to and into the cask and the contents thereof.

This drawback has been overcome by the present invention by which it is rendered possible to carry out the sterilization, preferably by means of sulphurous acid, only after the filling device has been applied to the cask and the filling tube has been introduced into the same to the required depth. Only then the requisite amount of the sulphurous acid or of the sulphur dioxide is introduced which evaporates instantly and produces a certain over-pressure in the cask whereby the sulphur vapor is caused to enter even into the finest pores of the wooden cask wall. After the vapor has acted in this manner upon the cask wall (or the inner surface of some other vessel, as the case may be) sterile air is blown through the filling device (which remains connected with the cask or other vessel) so that the sulphur dioxide is expelled from out of the cask etc., save a very small and not injurious remainder. Instantly thereafter the sterilized liquid is filled into the vessel. In this way a re-infection of the vessel and of the liquid is perfectly obviated, as the entire procedure is carried out in one continuous course.

The improved device for carrying out the improved method is illustrated diagrammatically and by way of example on the accompanying drawing on which Figure 1 is a front-view of the complete device in that position in which the filling takes place, the cask, the filling tube and a cylinder at the top being shown in section; Figure 2 is a side-view of the complete device, only the cask being shown in section; Figure 3 is an axial section, in side-view, of the top portion of the filling tube, in connection with certain members located above said top; Figure 4 is a plan of the members shown in Fig. 3; Figures 5 and 6 are side views of the uppermost parts of Fig. 4 in two different positions, and Figs. 7, 8 and 9 are detail views.

The filling device is of the usual design, as

customary with automatic cask filling devices; it can be reciprocated vertically by means of a cylinder 2^a suspended from any suitable part of a frame (not shown). A piston 2 enclosed in cylinder 2^a can be lifted by means of compressed air. Pressing said device upon the cask, at the bung hole of the same, is effected by the dead weight of the device. Introducing the compressed air into the cylinder 2^a and permitting it to escape therefrom is effected with the aid of a valve 1, the plug of which can be turned correspondingly. When the plug is in that position in which the compressed air present below the piston 2 can escape, compressed air is introduced into the cylinder chamber above said piston, whereupon this latter is depressed and all air present below it is driven out.

3 denotes the so-called pressing head which is to be placed upon the bung hole and closes it tightly. This head is actuated indirectly by the intermediary of the filling tube 4 which is rigidly connected with the piston rod 6 of the piston 2 by means of a so-called filling head composed of the members 10, 16, and 18 which are more fully described hereinafter. At the filling tube 4 is an abutment member 7 which when being lifted lifts in turn the pressing head 3, and when it is lowered places this head upon the bung hole, whereafter the filling tube is moved downwardly until it has attained its lowermost position. Tightening the head 3 on the bung hole is effected by the weight of the connecting rod 23 which is rendered somewhat heavier by an additional annular dead weight 5 surrounding the cylinder 2^a.

In the interior of the filling tube 4 is another tube 8, the lower end of which is provided with a closing valve 9 for said tube 4. To the upper end of this tube is attached a member 10 forming part of the casing and enclosing a rubber diaphragm 11 which is connected also with the inner tube 8. This diaphragm 11 serves on the one hand for the yieldable tightening of the tube 4, and on the other hand as a lifting member that is operated by the pressure of the liquid and tightens the filling valve 9 with respect to the filling tube 4.

The part 10 has a lateral lug 12 through which the liquid to be conveyed into the cask or other vessel is supplied in known manner from a container located on a higher level. At the upper end of the inner tube 8 is the so-called sterilizing head 13 which is designed as a casing and is provided with the injection valve 14 that is a diaphragm valve for the disinfecting agent, as well

as a cock 15 for the control of the scavenging gas, for instance sterilized air or carbonic acid or the like. The upper part 16 of said casing is rigidly connected with the arm 17 by means of two cheeks 18; this arm is guided by the telescopic tubes 19 which serve for conducting away the scavenging air or gas and the return air. Said cheeks 18 carry a bolt 20 upon which is supported the eccentric 21 and the lever 22 by means of which the eccentric can be actuated.

The guide rod 23 carries an adjustable holder 24 that is provided with two differently shaped abutment members 25 and 26. To the lefthand upper telescopic tube 19 is also attached a valve casing 27 enclosing a closing valve 28 which is opened by means of a rod 29 by the intermediary of a tipping lever 30 and a nose 31 of said lever when the downwardly moved filling member has arrived in its lowermost position. The valve 28 is closed by turning the lever 22 into its other position which is the filling position so that the return air from the cask can not flow through the lefthand telescopic tube, but is compelled to stream through the righthand telescopic tube, that air passing through the smaller lower telescopic tube 19^a which is firmly connected with the pressing head and is lifted and lowered together with it, and finds its way into the stationary upper and larger tube 19.

The diaphragm valve 14 is opened and closed at the upper end of the inner tube by means of the abutment members 25 and 26 and it is so designed that the rubber diaphragm is opened and closed by the intermediary of a pressing stamp which when being turned is at the same time lifted or lowered to a certain degree. When the cam lever 32 on its downward movement, as caused by the abutment member 25, is turned a little, the diaphragm valve is lifted so that the disinfecting agent which is supplied from a storage receptacle through the branch 33 runs into the interior of the tube 8 through bores 34, and passes from there into the cask. When the filling tube 4 descends further, the forked catch 35 of the cock plug 15 passes along an abutment member 36 which opens the cock 15 in the lowermost position of the filling tube. In the meantime the diaphragm valve 14 also has been closed by the abutment member 37 by the intermediary of the cam lever 32. When the filling tube rises after the cask or other vessel has been filled the cock 15 is automatically turned and the acid valve which is now closed moves in this position upwardly past the yielding abutment member 25. The filling valve 9 remains at first open while the filling member rises so that the liquid displaced by the filling tube is replaced. Only when the nose 31 of the lever 22 moves past the roll 39 of the abutment member 26 the lever 22 is turned back into the closing position, the valve being now closed by means of the diaphragm which is subjected to the pressure of the liquid.

In order to be able to adjust the height of the liquid in the cask etc. at liberty, the holder 24 is adjustable, and owing to the fact that this holder moves in the same manner as the guide rod which is rigidly connected with the pressing head it accommodates itself automatically to the size of the respective cask, whereby also the opening of the acid valve and the closing of the filling valve is effected automatically in the shorter or longer timed intervals according to the adjustment with consideration to the size of the cask or other vessel.

The apparatus is manipulated as follows:

The attendant first turns the plug of the cock 1 into the position shown in Fig. 9 whereby compressed air is permitted to flow into the upper chamber of the cylinder 2^a so that the piston 2 is moved downwardly and the pressing head 3 is consequently pressed upon the bung hole of the cask. Then the plug is turned into the position shown in Fig. 8 whereby the compressed air is compelled to flow through the narrow bore 38, in consequence whereof the filling tube is further lowered with a greatly reduced speed. While this tube is entering into the cask, first the diaphragm valve 14 is opened for the injection of the sterilizing agent and after a certain length of time said valve is again closed. When the filling tube has arrived in its lowermost position, the cock 15 is opened and sterilized air or carbonic acid or the like is introduced into the cask through the inner tube 8 in order to scavenge it. The gaseous scavenging product then leaves the cask through the lefthand telescopic tube and escapes into the open air through the open valve 28. A throttling member (not shown) inserted into said tube serves for keeping the pressure in the cask upon the desired counter-pressure during the filling operation. When the sterilization has been finished after about one minute, the lever 22 is so turned that the return air now passes through the righthand telescopic tube into the storage receptacle so as to establish a compensation of the pressures, and simultaneously therewith the filling valve is opened.

Now the cask or other vessel is being filled. This having been effected and finished, the air cock 1 is opened and the compressed air now flows into the chamber below the piston 2 whereby first the filling tube is lifted until the abutment member 7 contacts with the casing of the pressing head, whereupon said member takes this head along with it together with the two telescopic tubes 19^a. During this time also the filling valve 9 has been closed by the nose 31 contacting with the abutment member 39 whereby said nose is turned.

The filling cask or other vessel is now closed by means of an iron bung hole screw which has been sterilized together with the fastening plates, the closing proper being effected preferably with the aid of a magnetic box spanner, but instead of said screw also transverse disks or similar closing means may be used, it being understood that in every case they have been sterilized prior to their use.

I claim:

1. An apparatus for the sterilization and the sterile filling of vessels, comprising a slidable head for overlying the filling opening of the vessel, a guide rod on which said head is mounted, a filling pipe extending through the head into the vessel, means on said pipe for engaging the head, a rod for drawing the filling pipe into the vessel, a valve co-operating with the end of the filling pipe, inlet pipes for the sterilizing and scavenging agents, valves for controlling the admission of said agents, and abutments on the guide rod for actuating the valves during the movement of the filling pipe.

2. Apparatus for the sterilization and the sterile filling of vessels with liquor, comprising a pressing head having a passage therein, means for holding said head against the fill opening of the vessel, a filling tube adapted to extend through said head into the vessel, means for introducing sterilizing and scavenging agents into the vessel which are evacuated from the

vessel by the passage, and means for controlling the times and duration of the sterilizing, scavenging, filling, and head applying operations.

3. Apparatus for the sterilization and the sterile filling of vessels with liquor, comprising a pressing head having a passage therein, means for holding said head against the fill opening of the vessel, a filling tube adapted to extend through said head into the vessel, an inlet tube 10 extending through the filling tube for introducing a sterilizing agent into the vessel and for introducing a scavenging agent into the vessel which is evacuated from the vessel by means of the passage, and means for controlling the times 15 and duration of the sterilizing, scavenging, filling, and head applying operations.

4. Apparatus for the sterilization and the sterile filling of vessels with liquor, comprising a pressing head having a passage therein, means 20 for holding said head against the fill opening of the vessel, a filling tube adapted to extend through said head into the vessel, an inlet tube extending through the filling tube for introducing a sterilizing agent into the vessel and for introducing a scavenging agent into the vessel

which is evacuated from the vessel by means of the passage, means for controlling the times and duration of the sterilizing, scavenging, filling and head applying operations, said means including a valve on the inlet tube cooperating with a valve seat in the filling tube, and means for sliding the inlet tube relatively to the filling tube. 5

5. Apparatus for the sterilization and the sterile filling of vessels with liquor, comprising a 10 pressing head having a passage therein, means for holding said head against the fill opening of the vessel, a filling tube adapted to extend through said head into the vessel, an inlet tube extending through the filling tube for introducing a sterilizing agent into the vessel and for introducing a scavenging agent into the vessel which is evacuated from the vessel by means of the passage, valves controlling the admission of sterilizing and scavenging agents, and means 15 for operating said valves and the valve of the inlet tube in a predetermined sequence incidental to the movement of the filling tube. 20
